UNITED STATES PATENT OFFICE.

EDGAR KIDWELL, OF MILWAUKEE, WISCONSIN.

STEAM BOILER.

Application filed November 22, 1921. Serial No. 516,997.

To all whom it may concern:

Be it known that I, EDGAR KIDWELL, a citizen of the United States, and resident of Milwaukee, in the county of Milwaukee and State of Wisconsin, have invented certain new and useful Improvements in Steam Boilers, of which the following is a specification.

This invention relates to steam boilers; having reference, more particularly, to that type of boilers wherein transverse receptacles and associated banks of water tubes, together with suitable baffling, are employed, and wherein at least two of said receptacles are arranged partly above and partly below the normal level of the boiler water in order to constitute steam-and-water receptacles, whereof the respective steam-spaces are connected directly or indirectly by suitably-disposed drying or superheating tubes adapted to conduct the steam, which is liberated from the water in one receptacle, to the steam-space of the other receptacle preparatory to the discharge of the steam for service.

A boiler of the type mentioned is illustrated in my Letters Patent of the United States No. 1,348,179, dated August 3, 1920; the apparatus therein disclosed embodying main and supplemental water circulation paths so co-ordinated that the true level of the water within the steam-discharge receptacle is correctly indicated, irrespective of the fluctuations of the water-level in the steam-disengaging receptacle or other remote portion of the boiler, or the rate at which the boiler is being operated.

The present invention may be described as an improvement in or modification of the construction described in said Letters Patent, and particularly with respect to the supplemental water circulation path, as will be hereinafter described and claimed.

In the drawings—

Figure 1 is a longitudinal vertical section of a boiler of the transverse drum type embodying the principle of my invention.

Fig. 2 is a partial section showing the steam-and-water drums and the circulatory tube connections therebetween.

Fig. 3 is a similar view illustrating a modification of the tube connections.

Referring to the drawings, 10 designates the boiler setting; 11 the furnace therein,

and 12 the outlet or breeching to the smoke-stack at the rear of the setting.

13 designates a mud drum at the rear of the bridge wall of the furnace; 14 a water drum located above the forward portion of the furnace and below the normal water-level, and 15, 16 two steam-and-water drums arranged above the drums 13, 14, respectively. The drums 15, 16 are located partly above and partly below the normal water-level, thus providing in each a lower water-space 17 and an upper steam-space 18. The feed-water pipe 19 leads into the rear drum 15. The drums 13, 14 and 15 are connected in succeeding order by banks of tubes 20, 21, 22 respectively, thus providing a continuous circulation path for the water; and baffles 23 are suitably-disposed in relation to such banks in order to direct the hot gases and other products of combustion through appropriate passes from the front to the rear of the apparatus, whereby a continuous circulation of the water through the drums and tubes is effected.

The steam-space of the rear upper drum 15 is connected with the similar space of the front upper drum 16 by means of a series of tubes 24 which are preferably arranged within the path of the hot gases from the furnace, whereby the steam as rapidly as it is liberated from the water in the drum 15 flows into the steam-space of the front upper drum 16, such steam, during its passage through the tubes 24, being effectually dried or superheated. The drum 16 is provided with a discharge portion 25 through which the dry or superheated steam as rapidly as it is produced is taken off for service. This drum is also provided with a water-column, including the gage glass 29.

The parts above referred to are similar in construction and operation to the like-named parts described in the patent aforesaid.

In my prior construction water is diverted from the front water drum through suitable tube connections into the front steam-and-water drum which is outside the main path of circulation, such diverted water being thence directed through suitable tube connections to the rear steam-and-water drum which is included in the main path of circulation; the water thus diverted being of such volume that a steady water level in the front steam-and-water drum is main-

tained, irrespective of the disturbance of the water in the rear steam-and-water drum, or other remote portion of the boiler.

According to my present invention I dispense entirely with the tube connection between the two front drums 14, 16, and I connect the front and rear steam-and-water drums in such a manner that there is effected and maintained between the two drums 15, 10 16 a continuous water circulation which ensures a steady level of water within the front steam-and-water drum; such connection, together with the front steam-and-water drum, thus constituting a supplemental path 15 through which a portion of the main body of water is diverted from the main path of circulation.

The circulating connections between the drums 15, 16 comprise tubes 26, 27, respectively, which are so arranged in the heating zone of the furnace that the water is caused to flow from the rear drum to the front drum through the connection 26, and then to return from the front to the rear 25 drum through the connection 27. The volume of water circulating through the supplemental path constituted by the tubes 26, 27 and the front drum 16 is such as to ensure a constant level of the water within the latter irrespective of the fluctuations of the water within the steam-disengaging receptacle or other remote portion of the boiler, or the rate at which the boiler is being operated. The area of the tubes 26, 27 in relation 30 to that of the banks of tubes within the main path of circulation will, of course, vary with the size of the boiler.

One or more tubes 26 may be employed, the same, in the preferred form, being slightly curved downwardly adjacent the rear drum and then inclined upwardly in its path to the front drum. The connection of the tube or tubes 26 with the rear drum is made relatively low, while the connection with the front drum is made on a higher plane but below the water line. Hence provision is had for a steady and constant flow of water from the rear to the front drum. The tube or tubes 27 correspond in capacity 45 with the tube or tubes 26, and in the preferred form are curved downwardly at or adjacent the lower portion of the front drum and then inclined upwardly in its path to the rear drum. Preferably, though not necessarily, the tube connection 27 is constituted by one or more of the tubes of the bank 50 21, such tube or tubes being deflected upwardly at their forward ends and connected with the steam-and-water drum 16 instead of 55 with the water drum 14. Hence provision is had for a constant flow of water from the front to the rear drum, corresponding with the flow from the rear to the front drum, and, in consequence, the water line of the 60 front drum is maintained practically con- 65

stant even when sudden changes of load occur.

In the preferred form of my invention shown in Figs. 1 and 2, and above described, the tube 27 is provided with two curved ends which enter the drums radially, and the tube 26 is provided with one curved end which enters the adjacent drum, but it is to be understood that I do not limit my invention to any tube arrangement having a curved end or ends. Thus, for example, straight tubes may be employed, as shown in Fig. 3, such tubes entering the drum at any desired angle by using suitable pads.

It is also to be understood that I do not limit my invention to any arrangement in which the tubes cross each other, for the reason that if drums of sufficient diameter were provided tube 26 could be placed directly above tube 27, or vice versa.

I claim—

1. A steam boiler having a continuous main water circulation path and a supplemental water circulation path, said main path including a steam-and-water receptacle wherein the steam is disengaged from the water, and said supplemental path comprising a steam-and-water receptacle from which the steam is discharged from the boiler, said latter receptacle being outside the main path of circulation, and said supplemental path also comprising two tube connections between the water spaces of the two receptacles, one of said connections being inclined upwardly in its path from the steam-disengaging receptacle to the steam-discharging receptacle, and the other connection being inclined upwardly in its path from the steam-discharge receptacle to the other receptacle.

2. A water-tube boiler having front and rear transverse steam-and-water drums, a front water drum, a rear mud drum, a bank of tubes connecting said mud drum to the water drum, a second bank of tubes connecting said water drum to the rear steam-and-water drum, a third bank of tubes connecting said rear drum to the mud drum, supplemental circulating tube connections between the water spaces of the steam-and-water drums, one of said connections being inclined upwardly in its path from the rear to the front drum and the other connection being inclined upwardly in its path from the front to the rear drum, said connections being in the heating zone of the furnace, and superheater tubes connecting the steam spaces of the front and rear steam-and-water drums.

3. A steam boiler having a continuous main water circulation path and a supplemental water circulation path, said main path including a steam-and-water receptacle wherein the steam is disengaged from the water, and said supplemental path com-

prising a steam-and-water receptacle from which the steam is discharged from the boiler, said latter receptacle being outside the main path of circulation, and said supplemental path also comprising two tube connections between the water spaces of the two receptacles, one of said connections being inclined upwardly in its path from the steam-disengaging receptacle to the steam-discharging receptacle, and the other connection being deflected downwardly at the lower portion of the steam-discharging receptacle and then inclined upwardly in its path to the other receptacle, and steam-conducting means between the steam spaces of the two receptacles.

4. A steam boiler having a continuous main water circulation path and a supplemental water circulation path, said main path including a steam-and-water receptacle wherein the steam is disengaged from the water, and said supplemental path comprising a steam-and-water receptacle from which the steam is discharged from the boiler, said latter receptacle being outside the main path of circulation, and said supplemental path also comprising two tube connections between the water spaces of the two receptacles, one of said connections being inclined upwardly in its path from the steam-disengaging receptacle to the steam-discharging receptacle, and the other connection being deflected downwardly at the lower portion of the steam-discharging receptacle and then inclined upwardly in its path to the other receptacle, said connections being in the heating zone of the furnace, and steam-conducting means between the steam spaces of the two receptacles.

5. A water-tube boiler having front and rear transverse steam-and-water drums, a front water drum, a rear mud drum, a bank of tubes connecting said mud drum to the water drum, a second bank of tubes connecting said water drum to the rear steam-and-water drum, a third bank of tubes connecting said rear drum to the mud drum, supplemental circulating tube connections between the water spaces of the steam-and-water drums, one of said connections being inclined upwardly in its path from the rear to the front drum and the other connection being deflected downwardly at the lower portion of the front drum and then inclined upwardly in its path to the rear drum, said connections being in the heating zone of the furnace, and superheater tubes connecting the steam spaces of the front and rear steam-and-water drums.

Signed at Milwaukee in the county of Milwaukee and State of Wisconsin this 19th day of November A. D. 1921.

EDGAR KIDWELL.
